UNITED STATES PATENT OFFICE.

IDA M. HARRIS, OF WASHINGTON, DISTRICT OF COLUMBIA.

DRESS FORM.

Application filed July 7, 1920. Serial No. 294,418.

To all whom it may concern:

Be it known that I, IDA M. HARRIS, a citizen of the United States, residing at Washington, in the District of Columbia, have 5 invented certain new and useful Improvements in Dress Forms; and I do hereby declare the following to be a full, clear, and exact description of the invention, such as will enable others skilled in the art to which 10 it appertains to make and use the same.

This invention relates to dressmakers' dress forms and the primary object of the invention is to provide an improved dress form having the natural lines and configurations 15 of the human body, so that garments can be readily tried on the same and draped to obtain the most desirable effect.

Another object of the invention is to provide an improved dressmaker's form in 20 which the different portions of the body may be held in various positions so as to facilitate the fitting of the sleeves, and the like.

Another object of the invention is to provide an improved dressmaking form in 25 which the fabric forming the garment may be readily pinned to the form and thus held in position during the fitting of the garment to the form.

A further object of the invention is to 30 provide an improved dressmaker's dress form formed of compressible material, so that corsets of various shapes and styles may be fitted and adjusted on the form, without distorting the form in any way whatsoever, 35 so as to permit the form to take different configurations to conform to various and changing styles of figures assumed by women.

A still further object of the invention is 40 to provide an improved dress form of the above character, which is durable and efficient in use, one that is simple and easy to manufacture, and one that can be placed upon the market at a reasonable cost.

With these and other objects in view the 45 invention consists in the novel construction, arrangement and formation of parts, as will be hereinafter more fully described, claimed and illustrated in the accompanying drawings, forming a part thereof, in which:

Figure 1 is a front elevation of the improved dress form.

Figure 2 is a central vertical section through the same.

Referring to the drawings in detail, 50 wherein similar reference characters desig-

nate corresponding parts throughout the several views, the numeral 1 generally indicates the improved dress form, which includes a skeleton frame 2 formed of hollow tubing, and flexible wire of suitable gauge or other similar material.

The skeleton frame 2 includes the spaced bars 3 and 4 which form braces for the leg portions 5 of the figure, the central horizontal connecting bar 6, which forms the hip bar for the figure and the centrally disposed vertical bar 7 which is adapted to form the trunk part for the body. The bar 7 is connected at its lower ends to the central portion of the horizontal bar 6 and extends upwardly to the back 8 of the figure. The central body supporting bar has secured adjacent its upper end the outwardly extending bars 9 and 10 which form the shoulder portion 11 and arms 12 of the body. The bars 3, 4, 7, 9 and 10 are preferably formed in a plurality of sections and the sections are connected by flexible and bendable metallic tubings 13 which are coiled spirally and 50 formed similar to or the same as the support used in ordinary desk lamps. As clearly shown in the drawings the flexible, bendable hollow tubings 13 are arranged adjacent to the upper end of the legs of the 55 body, the waist and chest portion of the body, and the shoulder and elbow portions. This permits the body and arms to be placed in natural positions and held in such positions.

An outer skin or covering 14 is provided for the form and the same is preferably made of knitted fabric similar to the fabric used in making knitted union underwear for women's use and the body is stuffed with 95 a suitable compressible material 15, such as kapok silk, shredded wool rags and factory discard of wool. The terminals of the arms, legs and neck of the body are provided with metal caps 16 to which the fabric 14 is secured and the caps are further held in place by suitable collars 17.

The bars 3 and 4 forming the leg support extend below the stuffed portion of the body and secured to a circular floor engaging base 105 18 which is of sufficient diameter to support the form in an upright position against accidental displacement.

As stated the form is to be constructed to conform generally to the lines of the 110 human body preferably along the lines of a young lady and when a dress or garment is

to be made for a matured woman, bust pads 19 are detachably secured to the body of the form.

From the foregoing description, it can be seen that an improved dressmaker's dress form is provided which is of exceedingly simple and durable construction and which will permit the easy and ready fitting of garments thereon.

10 In practice, I have found that the form of my invention illustrated in the accompanying drawings and referred to in the above description, as the preferred embodiment, is the most efficient and practical; yet realizing the conditions concurrent with the adoption of my device will necessarily vary, I desire to emphasize the various minor changes in details of construction, proportion and arrangement of parts may be resorted to, when required without sacrificing any of the advantages of my invention as set forth.

What is claimed as new is:

1. A form of the class described consisting of a flexible covering and padding therein to simulate the shape of a portion

of a figure, and a frame member disposed within the padding and flexible throughout an elongated portion thereof to permit bending of the form along lines of gradual curvature.

2. A form of the class described consisting of a flexible covering and padding therein to simulate the shape of a portion of the figure, and a frame member disposed within the padding having an elongated spiral coil portion to permit bending of the form along lines of gradual curvature.

3. A form of the class described consisting of a flexible covering and padding therein to simulate the shape of a portion of the figure and a frame member disposed within the padding having elongated spiral coil portions to permit bending of the form at points substantially the same as the points of bending of the human figure.

In testimony whereof I affix my signature in presence of two witnesses.

IDA M. HARRIS.

Witnesses:

W. B. JOHNSTON,
J. E. DE CELL.
